[57] ABSTRACT

The disclosure involves a method and apparatus for advancing linear material or a bundle or bundles of fibers by substantially constant feeding means to a packaging station or stations at which the linear material is wound into package form, the feeding of the linear material being dependent upon sufficient tension and character of engagement of the material with the feeding means to assure positive feed but upon failure of tension to provide slippage interrupting the advance of the material. The disclosure includes processing a multiplicity of strands impregnated with a coating material wherein the feed method is individual to each strand and the winding station therefor, the arrangement providing for automatic interruption of an individual winder and advancement of strand thereto in event there is breakage or loss of tension in the strand delivered to such winder without affecting delivery of strands to other operating winders.

APPARATUS FOR PACKAGING LINEAR MATERIAL

This application is a continuation of application Ser. No. 731,209, filed May 22, 1968, now abandoned.

The invention relates to a method of and apparatus for packaging linear material such as a strand of fibers wherein a strand advancing or feeding means operated at a constant speed is associated with the linear material in a manner wherein slippage may occur in event of loss of tension in the linear material in order to assure that the material is fed to the winder at the rate at which the material is wound into a package with the material under substantially constant tension, the material feeding method and apparatus being particularly adaptable for use with an arrangement for impregnating or coating strands or bundles of strands of filamentary materials such as strands of glass filaments and packaging the impregnated or coated bundles of strands, the coating or impregnating material being of a character rendering the strands or bundles of strands particularly adaptable for forming tire cord or the like.

Heretofore difficulties have been encountered in endeavoring to feed strands withdrawn simultaneously from packages at a substantially constant linear rate and winding each strand or groups of strands on individual rotating collectors so that each wound package contains substantially the same amount of strand. The problem is particularly present in coating or impregnating a large number of strands and packaging the strands or groups of strands on individual collectors to obtain a high production yield of usable material.

The invention embraces a method of withdrawing linear material from a supply at a substantially constant tension by a rotating surface having frictional engagement with the linear material and winding the linear material on a rotating collector into a package and wherein reduction or loss of tension between the material advancing surface and the package being wound effects slippage of the linear material on the surface until the rotating collector attains a speed to wind the material at the rate the material is fed and proper tension established in the advancing linear material.

An object of the invention resides in a method of advancing linear material at a normally constant rate to a rotating collector for packaging the material by frictional engagement of the material with a rotating material feeding surface, the friction between the material and the feeding surface being dependent upon the linear contact of the material with the surface and the character of the surface whereby the rate of advancement of the material is automatic to assure proper collection of the material upon a rotating packaging collector.

Another object of the invention resides in a method of packaging a plurality of linear bodies for concomitantly winding each of the bodies upon an individual rotating collector, the bodies being advanced simultaneously, each at a substantially constant linear rate by engagement of the bodies with drive surfaces, one for each body and the surfaces simultaneously driven at a substantially constant speed, the character of engagement of each body with its independent feed surface being of a character whereby breakage of a linear body or loss of tension in the body permits slippage of the body on the feed surface to interrupt advancement of the body without tendency for the body to adhere to or wrap around the rotating feed surface.

Another object of the invention resides in feeding simultaneously a plurality of strands to a plurality of rotating collectors or winders for packaging each strand upon an individual collector wherein a plurality of rotating strand feeding surfaces, one for each strand, are concomitantly driven to normally advance all of the strands at the same linear rate, the character of each rotating feed surface and the linear contact of each strand with its respective surface being adapted to maintain the feed rate of each individual strand to its collector substantially constant whereby substantially the same amount of yardage is contained in each of the packages.

Another object of the invention is the provision of a method of packaging impregnated groups or bundles of strands and concomitantly packaging each individual bundle of strands upon a collector whereby each of the groups of strands is processed under substantially identical conditions of impregnation and collection to assure a uniform quality for all of the impregnated bundles of strands.

Another object of the invention resides in a method of maintaining substantially constant the tension in each of the strands and maintaining substantially constant the tension in each bundle or group of strands during the collection of the bundles or groups of strands on individual collectors.

Another object of the invention involves a method of impregnating the strands either individually or in groups, drying the impregnant on the groups of strands and establishing a common drive for the groups of strands whereby all the groups are subjected to substantially uniform driving tension and, in the event of breakage or loss of tension in a group, the drive for the particular group is interrupted without impairing the processing of the other groups being wound upon collectors.

Another object of the invention resides in withdrawing strands from supply packages wherein each strand is subjected to substantially the same tension and the strands grouped into bundles and impregnated with a coating material, the groups of strands being advanced to a drying station and the groups of impregnated bundles of strands advanced or driven by a common drive means whereby substantially uniform tension is established in each bundle of impregnated strands to promote uniform impregnation of the groups of strands.

Another object of the invention resides in withdrawing strands from supply packages and regulating the tension in each strand withdrawn from the package by a central control whereby each strand is subjected to substantially uniform tension.

Another object of the invention resides in a method of and apparatus for maintaining substantially constant uniform tension in groups of strands through a common drive for all of the groups wherein each group is wound upon an individual collector, the method and apparatus providing for interruption of the drive for any group in which breakage or loss of tension occurs without affecting continued winding of the other groups of strands.

Another object of the invention resides in a method of and apparatus for counting the revolutions of the common drive means for all of the groups and at each revolution an impulse is transferred to a counter at each of the winding or packaging stations and wherein loss of tension of a strand or breakage thereof is effec-

tive to interrupt the operation of the counter and interrupt the winding of such strand.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

FIG. 1 is a semischematic view illustrating a form of apparatus for performing the method of transferring linear material from a supply to form a wound package of material;

FIG. 2 is a sectional view of a form of means for applying tension to the linear material at the supply;

FIG. 3 is a semischematic elevational view illustrating the simultaneous feeding and collection of a plurality of impregnated linear bodies into wound packages;

FIG. 4 is a top plan view of the arrangement illustrated in FIG. 3;

FIG. 5 is a semischematic side elevational view of one of the package winders illustrated in FIG. 3 in association with a feeding means for the linear material;

FIG. 6 is a front elevational view of the arrangement shown in FIG. 5;

FIG. 7 is a plan view illustrating a modified arrangement of feeding strands through an impregnant;

FIG. 8 illustrates a counter actuating device;

FIG. 9 illustrates an electromagnetically actuated counter;

FIG. 10 is a schematic elevational view illustrating a common feeding means for a plurality of linear bodies, and

FIG. 11 is a top plan view of the arrangement illustrated in FIG. 10.

While the method and apparatus of the invention have particular utility in controlling the feeding of 40 coated strands whereby the strands are wound into individual packages with substantially the same amount of strand in each package, the invention may be utilized in transferring linear material or strand from a supply package onto a rotating collector wherever it is desirable to maintain constant the rate of delivery of linear material.

Referring to FIGS. 1 and 2 of the drawings, there is illustrated a form of apparatus for carrying out the method of the invention in feeding or transferring linear material such as a strand or body of glass fibers or filaments onto a rotating packaging collector of a conventional winding apparatus.

There is illustrated a single winder or winding machine of conventional character for winding a strand or other linear material into a package, the arrangement illustrating one form of feeding means and tension control for the strand or linear material.

A frame or creel 10 is provided adapted to mount or support a supply package 12 of linear material as, for example, a strand or bundle 14 of glass filaments. The strand 14 may be uncoated or may be coated or impregnated with rubber-like material or a similar impregnant. Mounted adjacent the package upon a support member 15 is a guide eye 16 for the strand and a tension control means 18 for controlling the tension of the strand withdrawn from the package, one form of

tension control 18 being illustrated in FIG. 2 and hereinafter described.

The strand 14 is passed through a guide eye 16 thence through the tension control 18 and over a guide 5 roll or pulley 20 to a device 22 illustrated schematically, the latter arranged to interrupt the circuit of a drive motor of the winder upon breakage of the strand or linear material 14. The strand or linear material 14 is engaged with a portion of the periphery of a feed roll 10 26, the latter being driven by a motor 28. Means is provided for regulating the length of linear contact of the strand 14 with the feed roll 26.

One form of means for this purpose is illustrated in FIG. 1 and includes a frame or support 30 disposed adjacent the feed roll, the frame including plate-like means 31 and 32 fashioned with slots 34 and 35. Adjustably mounted in the slots are members or stub shafts 36 and 37 each having a threaded portion accommodating a locking nut (not shown) for securing 20 the member in adjusted position.

Journally mounted on member 36 is a guide roll or pulley 39 and journaled on member 37 is a second guide roll or pulley 40. The strand 14 takes over the pulley 39 thence engages the peripheral surface of the 25 feed roll 26 and takes over the guide pulley or roll 40 and is fed to a rotatable collector on a winding machine 45, the latter being of conventional construction.

Initial tension in the strand or linear body 14 is established by the tension device 18, particularly illustrated 30 in FIG. 2. The material tensioning device 18 is of the "electromagnetically operated squeeze-type" and includes a tube 48 mounted upon the support plate 15, a coil 49 and annular disks 50 and 51 encircling the tube 48. The coil 49 is supported on a tubular member 53 of nonmetallic material, the coil 49 being insulatingly contained in a circular housing 55. The tube 48, member 53 and the coil housing 55 are secured to the plate 15 by a bolt 57 and a nut 58.

The annular disks 50 and 51 are rotatably supported on the tube or post 48, the disk 51 engaging and extending across the open end of the container 55, the disk 51 being preferably of nonmagnetic material.

The disk 50 is disposed adjacent the disk 51 with the strand or linear body 14 disposed between flat surfaces 45 of the disks 50 and 51. The disk 50 is fashioned of magnetizable material such as steel. Current is supplied to the coil 49 through leads 60 and 61, the coil being in circuit with an adjustable current regulating means 50 (not shown) for varying the magnetic flux acting on the disk 50 to regulate the amount of pressure and hence the amount of tension on the strand 14.

FIG. 1 illustrates in semischematic form a winding apparatus or machine 45 for winding the strand or linear body 14 into a package. The winder is of conventional construction of the character shown in U.S. Pat. No. 3,361,375. The winder is inclusive of a housing 64 which supports or encloses operating components and control means. The housing is provided with an upwardly extending frame portion 66 on which a winding head 68 is pivotally mounted, a winding mandrel 70 being journaled on the head and driven by an electrically energizable motor 72.

A thin walled collector or tube 74 is telescoped onto the mandrel 70, the linear body or strand 14 being wound upon the collector or tube 74 forming a wound package 75. An arm or member 76 is pivoted as at 78 on the housing 64 or on means carried by the housing,

the arm 76 having a grooved roll or pulley 80 journally supported at the distal end of the arm 76. As shown in FIG. 1, the strand 14 engages a guide roll or pulley 82 and the guide roll 80 on the arm 76 and is collected into a package 75 on the winding mandrel.

Mounted on the housing 45 is a member 84 supporting a rotatable traverse means 86 for the strand which also is reciprocated lengthwise of the package. The traverse guide 86 is reciprocated throughout the full length of the package during winding to form a square end package. The traverse guide 86 is rotated and reciprocated by means (not shown) driven by the motor 72. The traverse guide 86 is maintained close to the periphery of the package during its formation, the winding head 68 being pivotally supported on the shaft 88 whereby the head accommodates the increasing size of the package through the pivotal movement of the head 68.

The head 68 is biased in a counterclockwise direction by a spring 90 to maintain the surface of the package in contact with traverse roll or guide means 86. A bracket 92 is adjustably carried by the head 68 and a second spring 94 is connected with the bracket and with an anchoring member mounted on the frame 45. The biasing springs 90 and 94 are conventional and are employed to compensate for variable factors such as the initial weight of the head 68, the increase in package weight as package size increases and the decrease in the force vector as the head 68 is pivoted in a clockwise direction toward a vertical position through the axis of the shaft 88.

The motor 72 is of the variable speed type and is progressively reduced in speed as the package 75 increases in size during a winding operation so that the strand or linear body is wound at a substantially constant linear speed. The means for reducing the motor speed is controlled by potentiometers (not shown) the arrangement for controlling the motor speed being disclosed in U.S. Pat. No. 3,361,375.

The arm 76 when in its lowermost position, that is, when the strand or linear material loses tension and becomes slack or is broken, is arranged to engage a limit switch 98 intercalated in the circuit of motor 72 to de-energize the motor and interrupt the winding operation.

The feed roll 26 is engaged by the strand or linear body 14 to effect a substantially uniform linear feed of the strand to the collector 74. The character of the surface of the feed roll and the extent of lineal engagement of the strand 14 with the surface of the feed roll 26 provide for slippage of the strand on the feed roll during periods of start-up until the winding mandrel 70 is brought up to the proper winding speed and to facilitate slippage between the strand and the feed roll in the event that there is a loss of tension in the region of the strand between the feed roll 26 and the package being formed.

The character of the surface of the feed roll 26 is an essential factor in providing for slippage of the strand or linear body under certain operating conditions. The surface of the feed roll 26 may be fashioned of a material having the characteristic of permitting slippage of the strand 14 in the event of a slack condition of the strand 14 between the feed roll and the winder 45. It is found that a coating or surface of polyurethane on the feed roll 26 is effective when the strand 14 is in tension to feed the strand without slippage at a constant

linear rate as the feed roll 26 is rotated at a constant speed by the motor 28.

In a start-up operation, the strand 14 is in slackened condition between the feed roll and the winding collector 74 until the winding collector reaches proper winding speed which is equal to the normal linear feed rate of the strand or linear material advanced by the feed roll 26. With the strand in slackened condition slippage occurs between the feed roll and the strand until the slack condition in the strand 14 is obviated upon the collector 74 reaching its proper winding speed. If strand breakage occurs between the feed roll and the winder, slippage immediately ensues between the feed roll 26 and the strand so the feed of the strand is interrupted at the feed roll.

Furthermore, upon strand breakage, tension in the strand 14 is lost and the arm 76 moves downward to its lowermost position engaging the limit switch 98 to interrupt the circuit of the winding machine motor 72 to interrupt winding of the strand on the package 75. The amount of friction desired between the feed roll 26 and the strand 14 may be controlled by adjusting the relative position of one or both of the idler rolls 39 and 40 to modify the extent or length of linear peripheral contact of the strand 14 with the feed means or strand advancing roll 26.

While a layer or surfacing of polyurethane on the feed roll 26 has been effective as a satisfactory feed for the strand of glass filaments and provide for slippage under slack condition of the strand, other resinous materials may be used to advantage as a surfacing for the feed roll in conjunction with adjustment or control of the length of linear contact between the linear material or strand and the periphery of the feed roll 26. This characteristic or dimension may be varied by adjusting the idler rolls 39 and 40.

FIGS. 3 through 6 illustrate the method of the invention utilized with apparatus for impregnating or coating strands or bodies of linear material, such as strands of glass fibers with rubber, synthetic rubber or other impregnant, and feeding the strands by a common drive arrangement and winding each impregnated or coated strand or body on an individual collector whereby a large number of packages of coated or impregnated strand is simultaneously produced with each package having the same amount of strand. Each of the individual winders 45, one of which is shown in FIGS. 5 and 6, is the same as the winder shown in FIG. 1.

Referring to FIGS. 3 and 4, a creel frame 100 is fashioned to support tiers of supply packages 102 of strand, such as strand of glass filaments, whereby a substantially large number of supply packages is mounted upon the creel frame. The creel packages may be supported upon pins 104 mounted upon the creel frame.

Each of the strands 108 is fed through a guide eye through a friction device 18 of the character shown in detail in FIG. 2 to regulate the tension at the exit of the material from the supply package.

As shown in FIG. 4, the packages 102 of each horizontal row are arranged in laterally offset relation to facilitate withdrawal of the strands from the packages. A tension control means 18 hereinbefore described is provided for each individual strand or linear body. The energizable coil 49 of each of the tension controlling devices 18 is connected with a central or common adjustable current control means (not shown) whereby adjustment of the central control varies, modifies or

regulates the tension simultaneously in all of the strands.

A strand guide frame construction 112 is disposed adjacent and forwardly of the creel frame 100. The guide frame 112 is inclusive of spaced guide supporting portions 114 and 116. The guide frame portions 114 are provided with vertically spaced, transversely arranged rows of guide eyes 118, there being a guide eye for each strand or linear body 108, as shown in FIG. 4. The guide frame portion 116 is equipped with rows of guide eyes 120. As shown in FIG. 4, three strands 108 passing through three guide eyes 118 are converged into a single linear group or bundle 122 by passing the three strands through a single guide eye 120.

Thus, it will be seen from FIG. 4 that groups of the strands or linear bodies are combined into single linear bodies or strand groups 122. While three strands 108 are illustrated as forming one group 122, it is to be understood that any number of strands from individual supply packages 102 may be converged through each of the guide eyes 120 to form a single linear body or group. Positioned between the supply packages 102 and the guide eyes 118 and straddling each strand is a drop member or device 22 which functions to interrupt the motor circuit of the winder on which the group of strands incorporating the broken strand is being wound into a package.

The drop member switch device for accomplishing this function is disclosed in U.S. Pat. No. 3,361,375. A drop member switch device 22 is provided for each strand as indicated in FIG. 4. Each drop member 22 is normally held in open circuit or unoperable position by the normal tension in the strand. In event of breakage of a strand tension is lost and the drop member 22 falls by gravity to a position actuating a relay which deenergizes the motor 72 of the particular winder without affecting the other winders.

The groups of strands or linear bodies 122 are engaged with a horizontally disposed guide roll 126 arranged above a transversely elongated receptacle or tank 128 in which is contained an impregnating composition or coating material 130 in liquid or flowable condition. Immersed in the liquid impregnant is a roll 132 and disposed above the receptacle is a third roll 134.

As shown in FIG. 3, the groups of strands or linear bodies 122 pass downwardly into the impregnant 130, around the roll 132 thence over the third roll 134.

The linear groups or bodies 122 are spaced transversely as shown in FIG. 4 so that each group or body is isolated or out of contact with other groups or bodies so that upon immersion in the impregnant, each group or body is coated or impregnated with the liquid impregnating material 130. Extending transversely of the receptacle 128 is a wall portion 138 which supports stripping dies 140, there being a stripping die for each group or linear body 122a, the dies being for the purpose of stripping off excess impregnant adhering to the groups or bodies.

The stripped or excess impregnant is returned to the receptacle 128 along the wall portion 138. Through this arrangement each group or linear body 122 is effectively impregnated or coated with the impregnant or liquid material 130, the impregnated groups being designated 122a. The impregnant 130 is preferably rubber or synthetic rubber where the coated groups of strands or bodies are used in the fabrication of tire cord in the manufacture of pneumatic tires. It is to be understood

that other materials may be employed for impregnating or coating the strands or groups of strands dependent upon the end uses therefor.

The coated or impregnated strands or groups 122a of strands are passed through an oven or drying facility 144 in which air is circulated to volatilize the liquid constituent of the impregnant so that the impregnant or coating material on the strands is dried or substantially dried. The groups or bundles 122a of coated strands at the exit of the oven 144 are engaged with a guide roll 146. Means is provided in the oven or drying apparatus 144 to convey the coated groups or bundles of strand through the oven during start-up.

Disposed at respective end regions of the oven are sprockets 148 and 150, the sprockets being secured at the ends of the sprocket supporting shafts 152. Chains 154 and 156 connect a sprocket 148 and sprocket 150 of each pair, as shown in FIG. 4. The flights of chains 154 and 156 are equipped with bars or members 158 extending transversely of the oven 144.

The bars or members 158 provide means to which the strands or bundles of strands may be secured or anchored to facilitate start-up operations, the right-hand movement of the upper flight of the chains, as viewed in FIG. 4, drawing the bundles through the oven 144. In the event of breakage of a strand or bundle of strands, the same may be fastened to one of the bars 158 and such strand or bundle drawn through the oven after which the operator is enabled to thread the bundle over the feed and idler rolls and to the winder upon which the bundle is to be collected.

The groups or bundles of strands 122a from the drying facility 144 are directed to package winding machines or apparatus 45 of the character shown in FIG. 1 for packaging the coated or impregnated bodies, each group or bundle 122a being wound into a package on an individual winder 45.

The winders 45 are arranged in two lengthwise parallel groups. The invention includes a common drive means or feed means for the strand groups or linear bodies 122a delivered to each row of winders.

Disposed above each row of winders and extending lengthwise of each row is a rotatable shaft 162, each shaft being journaled in suitable bearings mounted upon a support or bar 166 extending parallel with the shafts, as shown in FIGS. 3 and 5. Each of the shafts 162 is arranged to drive body-advancing means or feed rolls 168, there being a feed roll 168 for each of the strand groups or linear bodies 122a. As shown in FIGS. 5 and 6, support members 170 are disposed parallel with the shafts 162.

Supported by brackets 171 mounted on each of the members 170 is a series of guide rolls or pulleys 172. Disposed adjacent the exit of the oven 144 and above the roll 146 is a guide roll 174 and all of the groups of strands or linear bodies 122a exiting from the oven 144 are passed beneath the guide roll 174 thence over the guide roll 174 from which each individual group or body 122a is directed over an individual guide roll or pulley 172, as shown schematically in FIG. 4.

FIGS. 5 and 6 illustrate the path of movement of each strand group or linear body 122a from a guide roll 172 onto the collector 74 to form a package 75. Each feed roll 168 is journally supported upon a bracket 176 mounted on the support 166.

Each feed roll is preferably driven from the adjacent shaft 162 through a magnetic type slip clutch contained

within a housing 178, this type of clutch being of a character used on a conventional textile twister frame.

Adjustably mounted about the axis of shaft 180 supporting a feed roll 168 is a bracket 182 which supports an idler roll or pulley 184 at its distal end. The bracket 182 has an elongated portion 186 and carries an adjusting screw 188 extending through an arcuate slot 190 in the support bracket 176. By manipulating the clamping screw 188 the bracket or member 182 carrying the idler roll 184 may be adjusted about the axis of the shaft 180 to change the relative position of the idler roll 184 with respect to the feed roll 168 to vary, adjust or control the extent of linear contact of the linear body 122a with the feeding means or roll 168 to thereby vary the amount of friction between a linear body 122a and the feed means 168.

The winder construction 45 shown in FIGS. 5 and 6 is substantially identical with the winder construction shown in FIG. 1. The group of strands or linear bodies 122a engages a guide roll or pulley 82 and passes around a pulley or guide 80 mounted upon the distal end of a pivoted arm 76 thence upwardly and is engaged by the traverse member 86 which distributes the linear body lengthwise of the collector 74 rotated by the winding mandrel 70 to distribute the linear body lengthwise in forming the package 75.

As shown in FIGS. 3 and 4, one of the drive shafts 162 is driven by a motor 192 and the other drive shaft 162 driven by a motor 194 at the same speed. The motors 192 and 194 are of a type rotating at a constant speed so that each drive shaft 162 is driven at a constant speed. The surface of each of the feed rolls 168 is of a character to establish a nonslipping friction drive for a strand group or linear body 122a when the linear body is under tension and, under loss of tension or reduced tension, permits the linear body to slip relative to the surface of a drive roll or feed roll 168.

When all of the winders of the two rows or banks of winders are in normal operation, each strand group or linear body 122a is advanced at a uniform speed because all of the strands are being advanced under the influence of drive shafts 162 both of which are rotating at a constant speed. In a situation at start-up where winding of a linear body is initiated on a winder on which an empty collector has been installed on the winding mandrel, a period of time is required to bring the winding collet up to normal packaging speed.

During this period there is no tension existent in the linear body 122a between the feed roll 168 and the winding collector. Hence, the linear body is not being advanced or fed by the feed roll 168 because the linear body is in a slack condition with insufficient friction or frictional engagement between the feed roll and the linear body to effect transfer of driving force to the linear body, this condition promoting slippage between the linear body and the feed roll 168.

This condition of providing for slippage resides in the character of the surface of the feed roll 168 and the length of linear contact of the linear body 122a with the surface of the feed roll. It has been found that by providing a surface on the feed roll 168 of a resinous material correlated with a proper length of engagement of the body with the feed roll surface, feeding of the strand group is attained when the strand group or linear body is in tension, and that slippage of the linear body relative to the feed roll surface occurs under a slack

condition or loss of tension condition in the linear body.

It has been found that a surfacing on the feed roll 168 of polyurethane presents a surface which fulfills the requirements of providing a positive feed for the linear body 122a under normal operating conditions and slippage under other conditions. When the linear material 122a is in a slack condition, slippage will occur but there is no tendency for the coated strands of a group 10 122a to adhere or stick to or wrap around the polyurethane surface even through the impregnant or coating of rubber or synthetic rubber may be slightly tacky or not completely set or dried in the curing oven.

The amount of friction under drive conditions with a 15 feed roll is in a measure dependent upon the amount of tension in the strand group 122a and the extent of linear contact of the strand group with the periphery of a feed roll.

The length of linear contact of the strand group with 20 the feed roll may be varied or controlled by adjusting the relative position of an idler roll 184 through manipulation of the locking member 188 to lengthen or shorten the extent of linear engagement of the strand group 122a with the polyurethane surface of the feed 25 roll 168.

Through the adjustment of the relative position of the idler roll 184, the amount of friction between the feed roll and the strand may be adjusted and correlated with the amount of tension in the strand group 122 between the feed roll 168 and the winder so that a positive drive or feed for the strand by the feed roll 168 is assured but slippage permitted only in the event of slack condition of a strand group during start-up operation of the winder or loss of tension for any reason in the strand group.

In the event of loss of tension in a strand group or breakage thereof, the feed of such strand group to a 30 winder is interrupted without affecting the winding operations of all of the remaining winders. Thus, in this form of the invention, only the winder failing to receive a strand group from its feeding means is rendered out of service. The drive rolls or feed rolls 168 are driven by a common drive, that is, the feed rolls for one bank or row of winders are driven by one drive shaft 162 by the constant speed motor 192, and the other group of 35 rolls 68 for the second bank of winders driven by a second shaft 162 at the same speed.

Each of the winding machines is equipped with an individual yardage counter or integrating device 208, the counters being of a type actuated by electric impulses, one of the counter or yardage integrating units being shown in FIG. 9. Mounted on each drive shaft 162 is a radially extending member or flag 200. Disposed adjacent the member 200 is a U-shaped electromagnetic 40 instrumentation 202. During rotation of a shaft 162, the member or flag 200 moves through the gap 204 of the instrumentation 202 which movement affects magnetic forces and thereby generates a pulse or signal in the output circuit of the instrumentation 202.

Each counter has an indicator 210 which continuously indicates, integrates or summates yardage accumulating on the package of strands. The counter is also equipped with a second indicating means 212 which may be manually set to predetermine the yardage to be wound in a package. The counter 208 includes a reset unit, recycling unit and a relay. The electromagnetic counter is of conventional construction such as a

Hecon counter, a product of Hengstler Numerics, Inc. As shown in FIGS. 3 and 4, one member 200 on each of the shafts 162 cooperates with an instrumentality 202. The circuit of the instrumentality 202 is connected to each of the counters 208 on each of the winding machines. Upon each rotation of the flag or member 200 through the gap in the instrumentality 202, an impulse is generated and impressed upon each of the counters to actuate the counters and indicate accumulating yardage.

The circuit of each counter is connected through a relay with the limit switch 98, associated with the arm 96, whereby in event of loss of tension in a strand bundle 122a between a feed roll and a winder, the arm 76 contacting the limit switch 98 renders the counter ineffective.

Thus counting of yardage on a particular winder is interrupted whenever there is loss of tension in the strand group 122a or in event of breakage of a strand bundle. A switch (not shown) embodied in the counter 208 is associated with the total yardage indicator 212 so that when the amount of yardage wound into a package 75 equals the predetermined yardage count on the indicator 212, the switch actuates a relay which interrupts the transmission of impulse signals from the instrumentality 202 to the counter and interrupts the circuit of the winder motor 72.

The counters, individual to each winding machine, are normally actuated by impulses generated through the instrumentality 202, but any abnormal condition arising in winding a strand bundle on a winder results in interruption of the transmission of the impulse signal to the counter on the particular winder and stops the operation of the winder. Hence, while an impulse signal at each revolution of a shaft 162 is transmitted to a counter on each of the several winders, the impulse will not actuate the counter of a winder if the strand group or bundle directed to the winder is not being accepted by the winder.

The counter 208 embodies a resetting means which, through the relay in the counter is actuated to return the counter to zero indication and prepare it for the next counting cycle of a package.

FIG. 7 illustrates a portion of an arrangement similar to that shown in FIG. 3 at the region of impregnation or coating of the strands with natural or synthetic rubber or other coating material. In this arrangement the individual strands 108' are drawn from supply packages 102', through tension devices 18', the strands moving past the drop member devices 22', thence through guide eyes 118' and 120' and engaging a roll 126'. The strands, while in transverse spaced relation, are drawn through the impregnant 130' in the container 128' and beneath an immersed roll 132'.

By drawing the individual strands 108' through the impregnant 130' with the strands in spaced relation, each strand is thus thoroughly impregnated or coated with the material. As shown in FIG. 7, the strands are converged into groups after they are passed through impregnant in the receptacle 128', there being three strands in each group, the groups passing over a guide roll 134', each group being drawn through a stripping die 140' and the groups 122b of coated strands conveyed through an oven or drying facility 144'.

The strand groups 122b are thereafter conveyed from the drying facility 144' to the several winders in the same manner as shown in FIGS. 3 and 4. Thus, in the

arrangement shown in FIG. 7, the strands are passed through the impregnant in spaced relation so that each strand is thoroughly coated or impregnated.

FIGS. 10 and 11 illustrate a modification wherein all of the strand groups delivered from a drying facility or oven are advanced to winding machines through the use of a common drive or feed roll. Disposed at the exit end of the drying facility 144' is an idler roll 146', the impregnated or coated strand groups 122c passing beneath the guide roll 146'. Disposed adjacent the exit end of the oven 144' is a frame structure 220 which includes members 222 disposed in transversely spaced relation. Journaled upon means (not shown) is a strand feed roll 240 mounted on a shaft driven by a constant speed motor 228.

Adjustably supported on the frame members 222 is a first idler roll 230 and a second idler roll 232. Each of the frame members 222 is provided with arcuately shaped slots 234 and 236. Tenon portions on the ends 20 of the rolls 230 and 232 extend through the slots 234 and 236 and are adjustable in the slots about the center of rotation of a feed roll 240. The idler rolls 230 and 232 may be held in adjusted position in the slots 234 and 236 by conventional securing means. In the arrangement shown in FIGS. 10 and 11, the surface or surfacing of the strand feed roll 240 may be polyurethane or other suitable resinous material as in the other forms of the invention.

The coated strand groups 122c take over the idler roll 230, thence engaging the surface of the feed roll 240 and the idler roll 232, the strands being directed over guide rolls or pulleys 172' and downwardly, each to an individual winding machine 45, where each coated strand group 122c is wound into a package.

In the form of the invention shown in FIGS. 10 and 11, all of the coated strand groups 122c are engaged with a common feed roll 240 whereby the strand groups are advanced to the winders 45 at the same linear speed.

In event of loss of tension in any strand group at a region between the feed roll 240 and a particular winder, slippage occurs between the strand in which the tension is lost and the feed roll 240. When tension is lost in a strand, the arm 76' of the particular winder engages a limit switch 98' to de-energize the winder motor 72 of the winder. During start-up of the winders, the individual strands may slip with respect to the polyurethane surface of the feed roll 240 until the proper tension is established in the strands fed to the several winders.

The idler rolls 230 and 232 are adjustable in order to regulate or vary the linear area of contact of the coated strand groups with the polyurethane surface on the feed roll 240. By controlling the linear engagement of the strand groups 122c with the surface of the feed roll 240 sufficient friction is established to provide for a normal positive feed of the strands to the winders and yet permit slippage between the feed roll and a strand group in the event of breakage of the strand group or loss of tension in the strand group. By providing the feed roll 240 with a polyurethane surface, in event of breakage of a strand group, the coated strand does not adhere to the polyurethane surface and hence the tendency for a broken strand to wrap around the feed roll 240 is substantially eliminated.

In the form of the invention shown in FIGS. 10 and 11, each of the winders 45 is equipped with an integrating device or counter of the type illustrated at 208 in

FIG. 9, each of the counters receiving electrical impulses from an arrangement of the character illustrated in FIG. 8, associated with the shaft carrying the feed roll 240 to summate or integrate the yardage accumulating on the collectors of the winding machines.

While polyurethane has been found to be very satisfactory as a surfacing component for the strand feed roll or rolls, it is to be understood that other resinous materials or compositions may be utilized for the surface of the feed rolls in order to establish a drive when the strand body is in tension and to provide slippage under loss of tension in the strand body.

It is apparent that, within the scope of the invention, modifications and different arrangements may be made other than as herein disclosed, and the present disclosure is illustrative merely, the invention comprehending all variations thereof.

We claim

1. Apparatus for packaging linear material comprising, in combination, support means, a rotatable collector mounted by the support means upon which the linear material is wound into a package, a motor for rotating the collector, feed means for advancing the linear material, said feed means including a rotatable feed roll engaging the linear material, means for rotating the feed roll, the tension in the linear material normally effecting frictional driving engagement of the linear material with the rotating feed roll, the driving engagement of the rotating feed roll with the linear material being rendered ineffective to advance the linear material upon loss of tension in the linear material, a movable member engaging the linear material at a region between the feed means and the rotating collector, and means actuated by the movable member upon loss of tension in the linear material to interrupt winding of the linear material on the collector.

2. Apparatus for packaging linear material comprising, in combination, support means, a rotatable collector mounted by the support means upon which the linear material is wound into a package, a motor for rotating the collector, feed means for advancing the linear material, said feed means including a rotatable feed roll engaging the linear material, means for rotating the feed roll, the tension in the linear material normally effecting frictional driving engagement of the linear material with the rotating feed roll, the driving engagement of the rotating feed roll with the linear material being rendered ineffective to advance the linear material upon loss of tension in the linear material, a pivotally supported member, a grooved guide mounted by said member engaging the linear material at a region between the feed means and the rotating collector, and means actuated by movement of the pivoted member upon loss of tension in the linear material to de-energize the motor rotating the collector to interrupt winding of the linear material on the collector.

3. Apparatus for packaging linear material comprising, in combination, support means, a rotatable collector mounted by the support means upon which the linear material is wound into a package, a motor for rotating the collector, feed means for advancing linear material, said feed means including a rotatable feed roll engaging the linear material, means for rotating the feed roll, the tension in the linear material normally effecting frictional driving engagement of the linear material with the rotating feed roll whereby the linear material is advanced by the feed roll at a substantially

constant speed to the collector, the driving engagement of the rotating feed roll with the linear material being rendered ineffective to advance the linear material upon loss of tension in the linear material, a movable member engaging the linear material at a region between the feed means and the rotating collector to maintain tension at said region in the linear material, said movable member being effective upon loss of tension in the linear material to de-energize the motor rotating the collector to interrupt winding of the linear material on the collector.

4. Apparatus for packaging linear material comprising, in combination, support means, a rotatable collector mounted by the support means upon which the linear material is wound into a package, a motor for rotating the collector, means for guiding the linear material into the package, feed means for advancing linear material, said feed means including a rotatable feed roll engaging the linear material, means for rotating the feed roll, the tension in the linear material normally effecting frictional driving engagement of the linear material with the rotating feed roll whereby the linear material is advanced by the feed roll at a substantially constant speed to the collector, the driving engagement of the rotating feed roll with the linear material being rendered ineffective to advance the linear material upon loss of tension in the linear material, a counter for integrating the amount of material in the package, said counter being actuated by impulses responsive to rotation of the feed roll, and means interrupting operation of the counter upon loss of tension in the linear material.

5. Apparatus for packaging linear material comprising, in combination, support means, a rotatable collector mounted by the support means upon which the linear material is wound into a package, a motor for rotating the collector, means for guiding the linear material into the package, feed means for advancing the linear material from a supply, said feed means including a rotatable feed roll having a peripheral surface of resinous material for engagement with the linear material, means for rotating the feed roll, the tension in the linear material normally effecting frictional driving engagement of the linear material with the rotating feed roll whereby the linear material is advanced by the feed roll at a substantially constant speed to the collector, the driving engagement of the rotating feed roll with the linear material being rendered ineffective to advance the linear material upon loss of tension in the linear material, a counter for integrating the amount of material in the package, said counter being actuated by impulses responsive to rotation of the feed roll, and means interrupting operation of the counter upon loss of tension in the linear material.

6. The combination according to claim 5 wherein the peripheral surface of the feed roll is of polyurethane.

7. Apparatus for packaging linear material including, in combination, frame means arranged to support a plurality of supply packages of strands of glass fibers from which the strands are withdrawn, means for applying coating material to the strands, a plurality of winding machines, each winding machine having a rotatable collector, means individual to each winding machine for rotating the collector, feeding means individual to each winding machine for withdrawing strands from the supply packages and advancing the strands to the winding machines, means for converging groups of

the strands from supply packages to form bundles of strand, means for drying the coating material on the strands prior to engagement of the bundles of strands with the feeding means, guide means for directing a bundle of strands to each of said feeding means, each of said feeding means including a rotatable feed roll engageable with a bundle of strands, each of said rotatable feed rolls being simultaneously rotated by a common drive means, means engaging each of the strands adjacent the supply packages for establishing tension in each of the strands, the tension in the strands normally effecting driving engagement of each bundle of strands with a rotating feed roll whereby each bundle of strands is advanced by the feed roll at a substantially constant speed to the collector of a winding machine, the driving engagement of a feed roll with a bundle of strands being rendered ineffective to advance the bundle of strands to the winding machine collector upon loss of tension in the bundle of strands.

8. Apparatus for packaging linear material including, in combination, frame means arranged to support a plurality of supply packages of strands of glass fibers from which the strands are withdrawn, means for applying coating material to the strands, a plurality of winding machines, each winding machine having a rotatable collector, means individual to each winding machine for rotating the collector, feeding means individual to each winding machine for withdrawing strands from the supply packages and advancing the strands to the winding machines, means for converging groups of the strands from supply packages to form bundles of strand, guide means for directing a bundle of strands to each of said feeding means, each of said feeding means including a rotatable feed roll engageable with a bundle of strands, said rotatable feed rolls being simultaneously rotated by a common drive means, means engaging each of the strands adjacent the supply packages for establishing tension in each of the strands, the tension in the strands normally effecting driving engagement of each bundle of strands with a rotating feed roll whereby each bundle of strands is advanced by the feed roll at a substantially constant speed to the collector of a winding machine, the driving engagement of a feed roll with a bundle of strands being rendered ineffective to advance the bundle of strands to the winding machine collector upon loss of tension in the bundle of strands, a yardage counter associated with each winding machine, and means responsive to the common drive means for the feeding means transmitting electrical impulses to the counter of the winding apparatus associated with the winding machines for integrating the yardage being packaged upon the collectors of each of the winding machines.

9. Apparatus for packaging linear material including, in combination, frame means arranged to support a plurality of supply packages of strands of glass fibers from which the strands are withdrawn, means for applying coating material to the strands, a plurality of winding machines, each winding machine having a rotatable collector, means individual to each winding machine for rotating the collector, feeding means individual to each winding machine for withdrawing strands from the supply packages and advancing the strands to the winding machines, means for converging groups of the strands from supply packages to form bundles of

strand, guide means for directing a bundle of strands to each of said feeding means, each of said feeding means including a rotatable feed roll having a surface of resinous material engageable with a bundle of strands, drive means for the rotatable feed rolls, means engaging each of the strands for establishing tension in each of the strands, the tension in the strands normally effecting driving engagement of each bundle of strands with a rotating feed roll whereby each bundle of strands is advanced by the feed roll at a substantially constant speed to the collector of a winding machine, the driving engagement of a feed roll with a bundle of strands being rendered ineffective to advance the bundle of strands to the winding machine collector upon loss of tension in the bundle of strands, a yardage counter associated with each winding machine, means responsive to the common drive means for the feeding means transmitting electrical impulses to the counters associated with the winding machines for integrating the yardage being packaged upon the collectors of each of the winding machines, a movable member associated with each winding machine and engageable with the bundle of strands being fed to the winding machine, and means actuated by movement of a member upon loss of tension in the bundle of strands engaged by the said member for interrupting the transfer of impulses to the counter of the winding apparatus associated with the bundle of strands in which loss of tension has occurred.

10. Apparatus for packaging linear material, in combination, frame means arranged to support a plurality of supply packages of strands of fibers from which the strands are withdrawn, means for applying coating material to the strands, means for converging groups of the strands to form a plurality of bundles of the strands, a plurality of winding machines, each winding machine having a rotating package collector on which a bundle of strands is wound into a package, a motor individual to each winding machine for rotating the collector, feeding means comprising a feed roll engageable with the bundles of strands for withdrawing the strands from the supply packages and advancing the bundles of strands to the winding machines, means for drying the coating material on the strands prior to engagement of the bundles of strands with the feed roll, said feed roll having its peripheral surface of resinous material for engagement with the bundles of strands, means for rotating the feed roll, the tension in the bundles of strands normally effecting frictional driving engagement of the bundles of strands with the rotating feed roll whereby the bundles of strands are advanced by the feed roll at a substantially constant speed to the collectors of the winding machines, the driving engagement for a bundle of strands being rendered ineffective to advance the bundle to its winding machine collector upon loss of tension in the bundle, a movable member for each winding machine engaging the bundle of strands being advanced to a winding machine at a region between the feed roll and the rotating collector of the winding machine to maintain tension at said region in the bundle of strands, and means actuated by a movable member upon loss of tension in the bundle of strands in engagement with the movable member to interrupt winding of the bundle on the collector.
